UNITED STATES PATENT OFFICE.

ANTHONY GEORGE LYSER, OF LIVERPOOL, ENGLAND.

HOPPER-BARGE.

SPECIFICATION forming part of Letters Patent No. 625,113, dated May 16, 1899.

Application filed June 27, 1898. Serial No. 684,542. (No model.)

To all whom it may concern:

Be it known that I, ANTHONY GEORGE LYSER, a subject of the Queen of Great Britain, residing at Liverpool, in the county of Lancaster, England, have invented new and useful Improvements in or Connected with Hopper-Barges or Hopper-Dredgers, (for which I have applied for a patent in Great Britain, No. 29,232, bearing date December 10, 1897,) 10 of which the following is a specification.

The object of this invention is to so construct or fit the hoppers of hopper-barges or hopper-dredgers used in suction-dredging that the escape of solid material with the overflow-water shall be more effectually prevented than is at present the case. For this purpose I form the hoppers with coverings watertight, or nearly so, and I provide one or more hollow shafts or trunks leading from the interior of the hoppers to a certain height above the covering, through which shafts or trunks the overflow-water rises and escapes over the upper edge. The number, area, height, and shape of the shafts or trunks are so proportioned that the velocity of the water rising therein is not sufficient to carry with it any or, if any, only a very small quantity of solid material, and the time also occupied by the water in passing from the discharge-pipe to 25 the upper edge of the shafts or trunks is such and the water in the shafts or trunks is so removed from the commotion in the hopper, caused by the inflow of the dredgings, that the material in suspension has plenty of time 30 and opportunity to deposit, and it is therefore left behind in the hoppers. It is advantageous that the discharge-pipe from the pumps should be at as great a distance as possible from the overflow shaft or shafts.

40 Valves or adjustable coamings are provided in or around the shafts or trunks, so that the discharge through such shafts can be regulated, thereby allowing of the deposit of material in the hopper being adjusted so as to trim the barge as desired.

Figure 1 is a longitudinal section, at the line A A on Fig. 2, of so much of a hopper-dredger as is necessary to illustrate my invention. Fig. 2 is a transverse section at the 45 line B B on Fig. 1. Fig. 3 is a longitudinal

section, at the line c c on Fig. 4, of a modification of my invention. Fig. 4 is a transverse section at the line D D on Fig. 3.

a is the hopper, of any usual form and provided with the usual dropping doors b at the 55 bottom, operated by chains in any usual way. The hopper is provided with a water-tight covering c. The covering c has openings which are surmounted by hollow shafts or trunks d.

e are valves in the shafts d, which valves are operated by levers, rods, and hand-wheels f, whereby the discharge of water from the shafts may be regulated to any desired degree, and thereby the deposit of material in 65 the hopper may be varied in amount at different points. The size, number, and position of the shafts d may be varied as found desirable, care being taken that the sectional area is such that the velocity of the escaping 70 water is not sufficient to carry with it any substantial quantity of the solid material, which material consequently settles down in the hopper. The head of water in the shafts d also reduces to a great extent the agitation of the 75 water in the hopper due to the rush of water from the discharge-pipe g of the dredging-pump. This discharge-pipe may be of any usual kind, preferably with valves and openings at different points, as usual, so that the 80 dredgings may be discharged into the hopper at various points.

Referring to Figs. 3 and 4, in which like letters indicate similar parts, as in Figs. 1 and 2, instead of several shafts being used, as in 85 Figs. 1 and 2, only one is used. This is placed at the center of the covering and is of oblong form, extending the whole length of the hopper, and instead of valves e being used the shaft d is provided with an adjustable coaming d' at each side. These coamings can be moved up or down in the guides d² by means of screws and hand-wheels f, so as to increase or diminish the head of water in the shaft d. By raising or lowering one end of the coamings d' more than the other end the escape of 90 water from the shaft can be varied at different points, or the coamings may be made in separate pieces each independently movable. Any suitable packing is provided, if required, 100

between the movable coamings and the sides of the shaft *d* to prevent escape of water between them.

I do not confine myself to the particular arrangements shown and described, as many modifications may be made; but

What I claim is—

1. A hopper barge or dredge having a covered hopper, and a hollow vertically-extending open-ended shaft or trunk extending from the covering to a height above it, and arranged to reduce agitation of the contents of the hopper and allow the deposit of dredged material while allowing free escape of water, substantially as described.

15 2. A hopper barge or dredge having a covering, and hollow open-ended shafts or trunks

extending upwardly from the covering to a height above it, and provided with mechanism for regulating the escape of water through 20 the shafts or trunks, substantially as described.

3. The combination with the hoppers of hopper-barges or hopper-dredgers of coverings and hollow shafts or trunks provided 25 with adjustable coamings or like devices adapted to regulate the escape and head of water so as to vary the deposit in the hopper at different points substantially as described.

ANTHONY GEORGE LYSTER.
